WHEEL MOUNTING FOR CENTRIFUGAL
CASTING MACHINES

Ferdinand Faber, Amberg Oberpfalz, and Christian Ostermann, Geisenkirchen, Germany, assignors to International De Lavaud Manufacturing Corporation, Limited, Jersey City, N. J., a corporation of Canada

Application June 3, 1939, Serial No. 277,178
In Germany June 13, 1938

4 Claims. (Cl. 22—65)

This invention relates to centrifugal casting apparatus, particularly to apparatus of the type in which the mold is reciprocably mounted on wheels and the pouring trough is mounted in a fixed position. The object of this invention is the provision of an improved wheel mounting for such molds comprising wheels on each side of the longitudinal center of the mold the bearing surfaces of which are inclined in relation to the horizontal. The rails over which the wheels travel are so positioned that the treads or bearing surfaces thereof are inclined similarly to the inclination of the bearing surfaces of the wheels.

Heretofore, the centrifugal machine have been mounted upon wheels, the axes and bearing surfaces of which were in horizontal planes, and the wheels were guided on the rails by the usual projecting rims. Due to the clearance necessary for such wheels, the machines sway sideways during their travel over the rails causing the pouring trough to be displaced relative to the mold, and uneven castings to be formed. The objectionable results of such sidesway are particularly aggravated in the case of small diameter molds where the displacement of the mold causes the pipe to have uneven wall thickness. The wheel mounting of the invention eliminates the aforementioned swaying difficulties. In a construction and arrangement of wheels and rails according to this invention, the wheels may travel over the rails without being guided by the rims. In order to insure rolling contact of the wheels on the rails without the frictional engagement of the rims, the wheel treads may be cylindrically formed and a suitable angular bearing or tread contact provided by inclining the wheel axles. The treads of the wheels may also be frusto-conical and the wheels mounted upon horizontal axles. In either case, the bearing surfaces or treads of the wheels on both sides of the machine are inclined with respect to the horizontal and with respect to each other, and the bearing surfaces of the rails are similarly inclined and preferably to the same extent. In a particularly advantageous construction, the tread surfaces of the wheels are inclined at an angle of about 45° relative to the horizontal. This inclination is particularly favorable from a standpoint of power transmission because the wheels travel in rolling contact with a minimum of side friction. The wheels are preferably cylindrical and the axles inclined about 45°, the inclination being such that the inclination of 55 towards a plane embracing the mold center.

each axle is towards a vertical plane embracing the mold.

The accompanying drawing illustrates more or less diagrammatically apparatus embodying the invention, in which:

Fig. 1 is a cross-sectional view of a centrifugal casting machine; and

Fig. 2 is a front view partly in section of a modified form of wheel mounting.

Fig. 1 illustrates the usual centrifugal casting machine comprising a housing 1, a rotatable mold 2, and a pouring trough 3. The casting machine is mounted upon any suitable number of wheels 4, preferably symmetrically disposed on each side of the longitudinal center of the machine. The wheels are mounted upon inclined axles 5 mounted in brackets 6 attached to the casting machine. The bearing or tread surfaces of the wheels 7 are more or less cylindrical and the inclinations thereof are generally in the same directions as the axles. The bearing surfaces 8 of the rails are coincident with the bearing surfaces of the wheels. In this particular form of construction, the inclination of each wheel axle is about 45° from the horizontal. The axles are inclined towards the vertical plane embracing the mold center and the load forces of the casting machine are radial from the mold, and the machine may travel along the rails with the wheels in perfect rolling contact without the rims 9 thereof being in frictional engagement with the side edges of the rails.

In the apparatus illustrated in Fig. 2, the wheels 10 are frusto-conical and are mounted upon a horizontal axle 11 which carries the casting machine on the brackets 12. In this form of apparatus, the rails 13 are preferably arranged similarly to those of Fig. 1, the bearing surfaces 14 thereof being inclined away from the horizontal and towards a plane embracing the mold center. The frustoconical surfaces of the wheels are such as to effect substantially uniform engagement with the treads of the rails, the degree of inclination of the wheel treads being similar to the inclination of the bearing surfaces of the rails.

It is to be understood that the inclination of the bearing surfaces of the wheels, and the bearing surfaces of the rails, may be differently inclined as by changing the mounting on the left for the mounting on the right, in which case the direction of load thrusts would not be radial as in the apparatus illustrated, but would converge

We claim:

1. In a centrifugal casting machine of the type mounted upon wheels which travel upon two side rails, the improvement which comprises constructing and arranging the tread surfaces of the wheels and of the rails so that they incline from the horizontal, whereby the wheels may travel in rolling contact with the rails without frictional contact of the rims therewith, and the casting machine is substantially free of side sway.

2. In a centrifugal casting machine mounted upon wheels and rails arranged on opposite sides of the longitudinal center of the machine, the

improvement which comprises, tread surfaces for the wheels which are inclined from the horizontal and tread surfaces for the rails inclined similarly to the tread surfaces of the wheels.

5. 3. A casting machine according to claim 2 in which the inclination of the wheel is about 45° with respect to the horizontal.

4. A casting machine according to claim 2 in which the inclination of the wheels on one side is opposite to the inclination of the wheels on the other side.

FERDINAND FABER.
